UNITED STATES PATENT OFFICE

168,297

EMBROIDERED TEXTILE FABRIC

David M. Goodstein, New York, N. Y.

Application April 15, 1952, Serial No. 19,334

Term of patent 3½ years

(Cl. D92—1)

To all whom it may concern:

Be it known that I, David M. Goodstein, a citizen of the United States, residing in New York city, in the county of New York and State of New York, have invented a new, original, and ornamental Design for an Embroidered Textile Fabric, of which the following is a specification, reference being had to the accompanying drawing, forming part thereof.

Fig. 1 is a plan view of an embroidered textile fabric showing my new design, and

Fig. 2 is the reverse side thereof.

I claim:

The ornamental design for an embroidered textile fabric, substantially as shown.

DAVID M. GOODSTEIN.
